UNITED STATES PATENT OFFICE.

OSCAR WINKLER, OF NAMSLAU, PRUSSIA, GERMANY.

BUNG-EXTRACTOR.

SPECIFICATION forming part of Letters Patent No. 411,179, dated September 17, 1889.

Application filed June 4, 1889. Serial No. 313,071. (No model.) Patented in Germany August 12, 1888, No. 46,613, and in Austria-Hungary January 24, 1889, No. 40,378 and No. 65,015.

To all whom it may concern:

Be it known that I, OSCAR WINKLER, a subject of the King of Prussia, residing at Namslau, in the Kingdom of Prussia, German Empire, have invented certain new and useful Improvements in Bung-Extractors, (for which I have obtained a patent in Germany, No. 46,613, dated August 12, 1888, and in Austria-Hungary, No. 40,378 and No. 65,015, dated January 24, 1889,) of which the following is a specification.

This invention relates to a bung-extractor provided with an annular head which is adapted to be pressed into the bung and to be then turned and raised, so as to loosen and remove the bung. It is well known that the method ordinarily used for the extraction of bungs from casks of different kinds is noisy, troublesome, and attended with great waste of time. My improved machine overcomes these objections, the cask from which the bung is to be extracted being rolled upon a movable support, with the bung placed below a suitably-shaped head, which can be moved up and down by a handle. A second handle is provided by which the head, when forced down into the bung, can be turned so as to loosen the latter and permit it to be raised. In this way the bungs can be removed from as many as fifteen hundred casks in ten hours, a speed quite unattainable under the old system.

The invention consists in the various features of improvement more fully pointed out in the claims.

In the accompanying drawings, Figure 1 is a side elevation of the entire machine. Fig. 2 is a sectional side view of the spindle. Fig. 3 is a perspective view of the head. Fig. 4 represents a side view and plan of the lever H'. Fig. 5 represents a side and front view of the stop. Fig. 6 shows a side and top view of the support or platform, and Fig. 7 is a side view of the crank.

The entire apparatus is attached to an upright post or standard P, fixed to the wall, and it consists, essentially, of an adjustable platform A for the cask, and a three-cornered wedge or spike-head D, carried at the lower

end of a spindle m, which can be moved up 50 and down. The platform A is supported upon a rack R, engaged by a toothed wheel Z, that may be revolved by the crank K. A pawl k' is thrown into engagement with rack R by spring f. By these means the platform A can 55 be quickly and easily raised or lowered to any desired height. The whole mechanism is covered by a plate B, which prevents chips from falling into it.

Above the platform A there is a spindle-shaft S, that can be moved up and down in guides F F', secured to standard P, and connected by rod T. A lever or handle H passes through a slot in the spindle-shaft S, to which it is pivoted, and its inner shorter end is also 65 connected by means of a short link L to the rod T. To the lower end of shaft S is fitted a spindle m, carrying a three-cornered spike-head or wedge D. The spindle m is connected to its shaft S by means of a screw-nut N. The spindle is flattened upon two of its sides, so that the forked end of a short lever or handle H' can be fitted upon it for the purpose of revolving the wedge or spike-head D. A forked arm or stop-plate V is fixed to the 75 lower side of the guide F', its forked end embracing the spindle m. When the head D is raised, the stop V will push the bung off the spike-head.

A special advantage resulting from the use 80 of this apparatus is that the casks are less injured than if the bungs are removed by hammers and similar tools. The bung-hole is for the same reason preserved from injury. Moreover, as no chips from the bung can enter the cask, the work proceeds without interruption.

What I claim is—

1. The combination of a supporting-frame with shaft S, and a spike-head having angular spindle m, adapted to be coupled to the shaft, and with lever H, pivoted to the frame and adapted to raise the shaft, and with a forked lever H', adapted to engage and revolve angular spindle m, substantially as 85 specified.

2. The combination of platform A with a rack R, supporting the platform, a toothed

wheel Z, and a spring-pawl h' , engaging the rack, a crank K, for revolving the toothed wheel, and with a sliding spindle having a three-cornered spike-head and supported in a frame above platform A, and with a pair of levers for imparting vertical and rotary motion to said spindle, substantially as specified.

In testimony whereof I hereunto sign my name, in the presence of two subscribing witnesses, this 8th day of May, 1889.

OSCAR WINKLER.
